Primary Examiner — Mary Ann Calabrese*Assistant Examiner* — Katelin G Kloberg(74) Attorney, Agent, or Firm — Larson & Larson; Frank Liebenow; Justin P. Miller(57) CLAIM

The ornamental design for a swing bed, as shown and described.

DESCRIPTION

FIG. 1 is a perspective view of a swing bed showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines depict chains that form no part of the claimed design.
